UNITED STATES PATENT OFFICE.

DANIEL C. RIPLEY, OF PITTSBURG, PENNSYLVANIA, ASSIGNOR TO UNITED STATES GLASS COMPANY, OF PITTSBURG, PENNSYLVANIA, A CORPORATION OF PENNSYLVANIA.

DESIGN FOR A LAMP-SHADE.

No. 39,743.

Specification for Design.

Patented Jan. 5, 1909.

Application filed October 13, 1908. Serial No. 457,580. Term of patent 7 years.

To all whom it may concern:

Be it known that I, DANIEL C. RIPLEY, of Pittsburg, Allegheny county, Pennsylvania, have invented a new, original, and ornamental Design for Lamp-Shades, of which the following is a specification, reference being had to the accompanying drawing, forming part hereof.

The figure is a perspective view of a lamp shade, showing my new design.

I claim:—

The ornamental design for a lamp shade, as shown.

In testimony whereof, I have hereunto set my hand.

DANIEL C. RIPLEY.
